UNITED STATES PATENT OFFICE

ULRICH KLOSS, OF BERLIN, GERMANY

DIRECT CURRENT RAILWAY SYSTEM

Application filed April 5, 1929, Serial No. 352,771, and in Germany February 15, 1929.

This invention relates to electric railway systems.

More particularly the same constitutes an additional embodiment of the invention set forth in my prior Patent No. 1,722,582 (application Ser. No. 263,729), in which I have described a method of disconnecting at a distance a certain zone or zones in the case of D. C. railway systems, that is to say depriving such zone or zones of current. As in the older patent, the invention is applicable to all systems in which a vehicle is propelled electrically over rails, and in which the track, as regards the supply of current, is divided into zones or sections, which are each supplied with current separately, and accordingly, as before, the term "railway" is employed in its broader sense to cover all systems of this kind, including for example tramway systems, although for better comprehension the invention is described with reference to a "railway" in its usually accepted meaning.

According to my prior Patent No. 1,722,582 (application Ser. No. 263,729), the sections or zones are disconnected either on the moving train or from the block sections by the actuation of a device provided on the train or at the block sections respectively, so that the substation is compelled to supply intermittent D. C. in the feed circuit, in order in this manner, by the use of a special transformer and a time relay, to actuate one or more automatic devices along the track. The intermittent D. C., according to the prior patent, is supplied through the medium of a make and break device provided on the train or at the block sections, this make and break device consisting in simple manner of contact producing elements.

Now under certain circumstances it is necessary to furnish the current to be interrupted with such strength or with such an interruption periodicity that owing to spark or arc formation the make and break device is strongly liable to be affected in detrimental manner.

I have also discovered that a further disadvantage in the method according to my said prior patent resides in the fact that

D. C. voltage as generated by rectifiers of the kind usually in use at the present time discloses an irregular pulsation or wave, that is to say, when employing a plurality of rectifiers, there is no synchronization in the operation thereof, so that in the feed circuit, which is common to all rectifiers employed, there is produced a certain fluctuation of voltage, which may cause the releasing mechanism to respond when not desired.

It is the object of the present invention to overcome the disadvantages referred to, and this is accomplished by employing in place of the mechanical make and break device referred to in my prior patent an ionic valve, the valve action of which as regards its influence on the cathode or the grid is well known. The desired action may be attained, for example by periodically completing and breaking the heating circuit of the cathode. The valve then allows current to flow in cadence from the travelling lead of the track to the rail return lead. The advantage arising from this system of connection resides in the fact that the heating current is much smaller than the interrupted current.

In an alternative form of embodiment it is possible, for example, to employ a grid tube, the grid of which is charged periodically positively or negatively by means of A. C., or the grid potential of which is periodically varied in relation to the cathode.

This form of embodiment has the advantage that no mechanical make and break devices are required. Consequently any desired periodicity of interruption is possible.

The use of tubes as interrupting elements furthermore allows the interrupting and releasing device to be tuned to any particular periodicity as desired, so that in this manner it is possible to avoid the disturbing range of the harmonic vibration of the rectifiers, and by using different tuning to establish connection with certain stations only. It is moreover then also possible to communicate other intelligence beyond the disconnection.

This arrangement may also be used in conjunction with A. C. systems. The sub-

station in this case supplies intermittent A. C., and a superposing of the intermittent impulses with the A. C. fundamental wave occurs.

In order to allow of better filtering of the fundamental wave (this may be direct voltage with and without harmonic vibrations or alternate voltage) of the feeding station from the interrupting wave utilized for releasing purposes, it is preferable to employ the releasing transformer, which in my prior patent is connected across the feed line of the sub-station and constitutes a pure through transformer, in shunt with a choker. The shunt circuit by reason of its nature (proper selection of capacity and inductance) then allows merely the interrupting impulses of higher frequency to pass, which in the tuned or non-tuned circuits cause the release of the automatic devices, or transmit other intelligence to the station, while the low-frequency vibrations of the fundamental wave of the station pass through the choker.

The use of a tube as interrupting element finally has the advantage that the same allows at the most passage of the saturation current. A limiting resistance as in the case of a mechanical make and break device is not required.

When the automatic device along the track is released, the connecting coil of the automatic device is simultaneously connected at the sub-station to the travelling lead and the rail return lead. The driver of the train is then in a position to supply by the use of a safety connection voltage for reconnection purposes to the thus directly connected connection coil of the automatic device from the battery of the locomotive.

The invention is illustrated by way of example in the accompanying drawing, in which

Fig. 1 is a diagram of connections at the sub-station with a tube interrupter on the train.

Fig. 2 is a modification of the tube interrupter on the train.

Fig. 3 is the diagram of connections for a tube interrupter which is provided on the train and is capable of being tuned.

Fig. 4 is a corresponding diagram for the sub-station.

Fig. 5 is the diagram of a special form of embodiment at the sub-station.

Referring now to Fig. 1, the sub-station is designated by the reference character A, while B represents a moving train. At the sub-station 1 is the dynamo or converter, which serves to feed the current rail 4 through the medium of the automatic devices 2 and the track automatic devices 3. The other pole of the dynamo is connected via the collecting bar 5 to the travelling rail 6. Between the track automatic device 3 and the contact rail 4 is the through trans-

former having the primary winding 7 and the secondary winding 8. The secondary winding is connected with a time relay 9, which serves for closing the two contacts 10 and 11, in such manner that along the lead 12 the current proceeding from the local battery 14 is able to pass via the disc drop indicator board 13 to the releasing coil 15 of the track automatic device 3. The core 16 of the coil is connected in such manner with the track automatic devices that upon completing the circuit over the contacts 10, 11 the track automatic device is actuated by the battery 14 and the current is cut off from the contact rail. In place of the make and break device described in my prior Patent No. 1,722,582 (application Ser. No. 263,729) I employ in accordance with the present invention a device provided on the train or vehicle B or at a block section, which device consists of an electron discharge tube 17 having an anode 18 and a hot cathode 19 fed by the heating battery 20. The heating circuit includes a make and break device 21, which may be actuated in such manner by an operating device 22 that the heating circuit for the cathode is continuously broken and closed. The anode is connected with the interposition of a resistance 23 to the travelling lead 4, while the hot cathode 19 is connected at 24 with the travelling rail 6. By alternately closing and breaking the heating circuit for the cathode 19 the electron current flowing between anode and cathode will be broken and closed continuously, so that these current impulses are caused to act in the transformer 7, 8 and operate the time relay 9, actuating the track automatic devices 3 over the contacts 10, 11 via the releasing coil 15. The make and break device 21 is subject to only very slight load under current in accordance with the low heating current for the hot cathode 19.

A modified form of embodiment of the interrupter is illustrated in Fig. 2. The electron discharge tube 17 contains in addition to the anode 18 and the hot cathode 19 a grid 25. An alternate voltage is impressed upon this grid by means of an A. C. generator 26, so that an interruption of the electron current occurs in conformity with the periodicity of the alternate current, this causing actuation of the track automatic devices as in the case of the embodiment described above. In place of an A. C. generator 26 it is also possible to employ any other device supplying the grid with continuously varying voltages.

Fig. 3 shows an additional form of embodiment employing an electron tube. In this case the electron tube 17 also has the object of intermittently shortcircuiting the travelling voltage. This, however, is not a shortcircuiting within the ordinary sense of the word, as each electron tube allows pas-

sage at the most of saturation current. The connection impulse of the device is sufficient to start the secondarily connected oscillatory circuit, which then acts in selective 5 cadence on the grid and thus causes the short-circuiting periodicity to be harmonized.

At the sub-station there is, as shown in Fig. 4, a corresponding releasing device, which serves for actuation of the releasing relay for 10 the track automatic device. The said releasing device includes a high frequency transformer, consisting of the primary coil 28 and the secondary coil 29. The primary coil 28 is situated directly in the connection between 15 the collector bar and the travelling lead. The condenser 30 serves for tuning purposes with the use of an electron tube 31, the grid potential of which is acted upon by the shortcircuiting periodicity produced on the train. It 20 is thus possible on the train to disconnect as desired a certain sub-station without affecting the others.

Fig. 5 shows a somewhat modified form of embodiment of Fig. 4. In lieu of the high 25 frequency transformer, which may have certain disadvantages, there is provided in the connection line between travelling lead and collector bar a choker 33. Connected to this choker, through the medium of a condenser 30 34, is the primary coil 35 of a high frequency transformer, the secondary coil 29 of which is connected with the remaining parts of the device in the manner described in the case of Fig. 4.

35 It will be understood that no restriction is made to the specific forms of embodiment shown, and that various modifications may be made without departing from the spirit of the invention.

40 What I claim as new and desire to secure by Letters Patent is:

1. An apparatus for disconnecting the feed circuit of track zones of direct current railways from a moving train or block section 45 at a distance, comprising an automatic switching device in said feed circuit, a control circuit reactively coupled to said feed circuit, a local circuit closed by said control circuit and electro-magnetically actuating 50 said automatic switching device, and electronic tube means making and breaking the feed circuit thereby indirectly causing said automatic switching device to open.

55 2. An apparatus for disconnecting the feed circuit of track zones of direct current railways from a moving train or block section at a distance, comprising an automatic switching device in said feed circuit, a control circuit reactively coupled to said feed circuit electro-magnetically actuating said automatic switching device, a time relay connected in said control circuit and mechanically closing 60 said local circuit, electronic tube means in said feed circuit and means interrupting the flow of electrons in said electronic tube means at the tuned frequency of said tuned oscillating control circuit causing operation of said automatic switching device.

65 3. An apparatus for disconnecting the feed circuit of track zones of direct current

70 rupting the flow of electrons in said electronic tube means.

3. An apparatus for disconnecting the feed circuit of track zones for direct current railways from a moving train or block section at a distance, comprising an automatic switching device in said feed circuit, a control circuit reactively coupled to said feed circuit, a local circuit electro-magnetically actuating said automatic switching device, 75 a time relay connected in said control circuit and mechanically closing said local circuit, electronic tube means in said feed circuit, a cathode and anode in said electronic tube means, a heating circuit for said cathode and mechanical means for periodically interrupting said heating circuit.

4. An apparatus for disconnecting the feed circuit of track zones of direct current railways from a moving train or block section at a distance, comprising an automatic switching device in said feed circuit, a control circuit reactively coupled to said feed circuit, a local circuit electro-magnetically actuating said automatic switching device, 80 a time relay connected in said control circuit and mechanically closing said local circuit, electronic tube means in said feed circuit, a cathode, anode and grid in said electronic tube means and electrical means impressing an alternating voltage on said grid.

5. An apparatus for disconnecting the feed circuit of track zones of direct current railways from a moving train or block section at a distance, comprising an automatic switching device in said feed circuit, a control circuit reactively coupled to said feed circuit, a local circuit electro-magnetically actuating said automatic switching device, a time relay connected 100 in said control circuit and mechanically closing said local circuit, electronic tube means in said feed circuit, a grid in said electronic tube means and an oscillating tuned circuit inductively coupled to said feed circuit and impressing alternating voltage on said grid.

6. An apparatus for disconnecting the feed circuit of track zones of direct current railways from a moving train or block section at a distance, comprising an automatic switching device in said feed circuit, a tuned oscillating control circuit reactively coupled to said feed circuit, a local circuit electro-magnetically actuating said automatic switching device, a time relay connected in said control circuit and mechanically closing said local circuit, electronic tube means in said feed circuit and means interrupting the flow

110 of electrons in said electronic tube means at the tuned frequency of said tuned oscillating control circuit causing operation of said automatic switching device.

7. An apparatus for disconnecting the feed circuit of track zones of direct current

15 railways from a moving train or block section at a distance, comprising an automatic switching device in said feed circuit, a tuned oscillating control circuit reactively coupled to said feed circuit comprising a tuned oscillating circuit, an anode, cathode and grid, said grid being connected to said tuned oscillating circuit and a time relay connected to said anode and cathode, a local circuit electro-magnetically actuating said automatic switch device and closed by said time relay, electronic tube means in said feed circuit, a grid in said electronic tube means and an oscillating tuned circuit inductively coupled to said feed circuit and impressing alternating voltage on said grid.

20 8. An apparatus according to claim 6 wherein the reactive coupling of said control and feed circuits comprises a choke coil in said feed circuit, a high frequency transformer having the primary thereof connected through a capacitance across said choke coil, the secondary of said transformer being in said control circuit.

25 9. Apparatus for disconnecting a particular feed circuit of track zones of direct current railways from a moving train or block section at a distance, comprising a plurality of automatic switching devices in each feeding circuit, a plurality of tuned oscillating control circuits of definite and different tuned frequencies reactively coupled to each feed circuit, local circuits electro-magnetically actuating each automatic switching device, time relays connected in said control circuits and mechanically closing each local circuit, electronic tube means in each feeding circuit and means interrupting the flow of electrons in each electronic tube means at the tuned frequency of the particular control circuit to be energized and to isolate a particular track zone.

30 In testimony whereof I have affixed my signature.
